UNITED STATES PATENT OFFICE.

JACOB DOBBINS, OF LITCHFIELD, MICHIGAN.

IMPROVED MACHINE FOR JOINTING AND DRESSING STAVES.

Specification forming part of Letters Patent No. 36,705, dated October 21, 1862.

To all whom it may concern:

Be it known that I, JACOB DOBBINS, of Litchfield, in the county of Hillsdale and State of Michigan, have invented a new and Improved Machine for Dressing and Jointing Staves; and I do hereby declare that the following is a full, clear, and exact description of the same, reference being had to the accompanying drawings, making a part of this specification, in which—

Figure 1 is a front elevation of my invention. Fig. 2 is a side elevation of the same. Fig. 3 is a plan or top view of the same; Fig. 4, a horizontal section of the same, taken in the line *x x*, Fig. 2; Fig. 5, a section of Fig. 4, taken in the line *y y*.

Similar letters of reference indicate corresponding parts in the several figures.

This invention relates, first, to an improved means for dressing the staves, whereby the work may be performed expeditiously and in a perfect manner, and made to operate upon stuff of different thicknesses, as well as being capable of being adapted to operate upon winding stuff.

The invention also relates to an improved means for jointing the staves, whereby staves of different widths may be acted upon and beveled in a perfect manner, and the barrel-heads also planed.

To enable those skilled in the art to fully understand and construct my invention I will proceed to describe it.

A represents the frame of the machine, which may be constructed in any proper way to support the working parts, and *B* is a horizontal shaft, which is placed in proper bearings on the frame *A*, and has two flanges, *a a*, projecting from it at opposite sides, said flanges being of hooked or bent form, so that cutters *C C* may be attached thereto and have a tangential position relatively therewith. On the shaft *B* there are also secured two flanges, *b b*, projecting from it at opposite sides and at right angles to the flanges *a a* of the cutters *C C*. The flanges *b b*, like *a a*, are of hooked or bent form, so that cutters *D D D' D'*, which are attached to them, may have a longitudinal position relatively with the shaft *B*. The cutters *D D'* are of curved form, one being curved in a reverse manner to the other, as shown in Fig. 1. The cutters *C* are nearly or quite

straight. Their inner ends may be slightly curved toward the shaft *B*, as shown in Fig. 3.

On the shaft *B*, near one end, there is secured a pinion, *c*, into which a toothed wheel, *E*, gears. This wheel *E* has the bearings of its axis *d* in a small frame, *F*, which is secured to the frame *A*, and *F'* is a yielding frame, which is secured by pivots *e* to the frame *A*, and has a plate, *f*, in its front part, which is made to bear against a spring, *g*, by a set-screw, *h*, which passes through the lower part of *F*, the spring *g* being attached to the frame *A*, as shown in Fig. 5. On the inner end of the axis *d* of the wheel *E* there is a pinion, *i*, which gears into a pinion, *j*, the axis of which is in the frame *F'*, and has a smaller pinion, *k*, attached to it. The pinion *k* gears into a segment-rack, *G*, on one side of a segment-bed, *H*, which is secured to the upper end of a radius-bar, *I*, the lower end of which is fitted loosely on a shaft, *l*, in a frame, *J*, which is placed loosely on a rod, *m*, in a frame, *K*, the latter being fitted loosely on a rod, *n*, in the lower part of the frame *A*. This frame *K* may be adjusted higher or lower by means of a screw-rod, *L*, which passes through the upper end of a bar, *M*, attached to frame *K*. By turning the screw-rod *L* the frames *J K*, and consequently the bed *H*, may be adjusted higher or lower, so as to admit of a greater or less space between the cutters *D D' D' D'* and the bed *H*. The frame *J*, in which the lower end of the radius-bar *I* is secured, is retained in proper position by a catch, *M'*, which has a spring, *N*, bearing against it, the spring having a tendency to keep the catch engaged with a lip or projection, *o*, attached to frame *J*. (See Fig. 2.) The catch *M* is formed simply of an upright bar, *p*, attached to a rock-shaft *q*, the bar *p* having a recess made in it to receive the lip *o*. To the front side of the radius-bar *I* there is attached an adjustable angle-plate *O*, which serves as a rest for the bar *I* when the frame *J* is released from the catch *M'*, the plate *O* bearing on the rod *m* in the frame *K*.

P is a set-screw, which passes through the lower part of the bar *L*, and serves to disengage the catch *M'* from the frame *J* when the bed *H* has reached the termination of its forward movement.

The bed *H* is slotted longitudinally and centrally to receive a clamp-bar, *Q*, the front end

of which is hung loosely in a frame, R, in which the bed H is secured, and in this clamp-bar Q a slide, S, is fitted and adjusted by a screw, T, the slide S having two jaws, *t t*, attached to it, which are in line with two fixed jaws, *u u*, at the back end of the bar Q. The frame R is a jointed one, or formed of two parts, *v v'*, the upper one, *v'*, being suspended loosely from the upper part of the frame A. (See Fig. 2.)

On the front part of the frame A there are placed two swinging bars, U U, which serve as supports for the clamp-bar Q, while the staves are being adjusted or dogged between the jaws *t t u u*, and one is made larger than the other, so that they may serve as a gage to indicate the thickness of the staves. The bars U U are simply curved pieces of metal hung loosely on horizontal shafts *w*, and loaded at their lower ends, as shown at *w'*, in order that their upper ends when not in use may be kept apart.

The operation of the above-described parts is as follows: The shaft B is rotated by any convenient power, and two staves are adjusted or dogged to the clamp-bar Q by turning the screw-rod. The bed H is then adjusted higher or lower by turning the screw-rod L so as to suit the thickness of the staves. The frame F' is also adjusted by means of the set-screw *h*, so that the pinion *k* may gear properly into the segment-rack G, the lip *o* of frame J being adjusted in the bar *p* of catch M'. The bed H is fed or moved forward in consequence of the pinion *k* gearing into the rack G, and the staves are dressed one in concave and the other in convex form by the cutters D D'. When the bed reaches the end of its forward or feed movement, the screw P strikes the bar *p* of catch M', and disengages the latter from the frame J, which falls sufficiently to disconnect the rack G from the pinion *k*, and the bed will be forced back to its original position by a spring, *k'*, connected to the frame R. The staves are then reversed in position on the bed H—that is to say, inverted, and the one with the concave surface placed under the concave cutter, and the one with convex surface placed under the convex cutter. The bed H is then adjusted as before, and again fed forward, and the opposite sides of the staves are cut. The staves are thus dressed on both sides and ready to be jointed.

The jointing apparatus is composed of the cutters C C, previously described, and a clamp for holding the staves, which is placed on a sliding frame, V, said frame being allowed to move freely in the frame A, and connected at its back end to a swinging frame, W, suspended from the frame A. The sliding frame V is fitted in guides *b' b'*, attached to vertical bars *c' c'*, which will admit of being raised and lowered, so that said frame V may be adjusted higher or lower, as may be desired. On the front end of the frame V there is secured, by a central bolt or pivot, a rectangular block, X, on which a bolster, Y, is

secured, the upper surface of which is curved longitudinally or in the direction of its length corresponding to the bilge to be given the staves, and directly over the bolster Y there is a clamp-bar, Z, the ends of which are each provided with a recess, *d'*, to fit on vertical bars *c'*, attached to each end of the block X, the bars *c'* serving as guides for the clamp-bar. The upper ends of the bars *c'* are connected by a curved bar, *f'*, through the center of which a screw, A', passes and bears upon the center of the clamp-bar Z.

B' is a treadle, which is in the lower part of the frame A, and is connected to two vertical rods; C" C", which extend upward in front of the vertical bars *c'*. The upper parts of the rods C" C" are beveled at their front sides, and when the frame V is pressed forward it bears against the beveled surfaces of the rods C" C", and as the latter are depressed by the action of the foot of the operator on the treadle B' the stave, which is clamped on the bolster Y by the clamp-bar Z, will be jointed by the cutters C C. When a stave is jointed at one side, the block X is reversed in position, (turned half a revolution on its pivot,) which brings the opposite side of the stave in front of the cutters, and the other side of the stave is jointed.

I would remark that the frame W of the slide V may be connected to the frame R of the bed H, so that the slide V may be moved automatically with the bed H. The bilge of the staves is regulated by the set of the cutters C C and by the curve of the bolster Y, and the bevel is regulated by the vertical adjustment of the frame V.

The cutters C C may be used for planing the barrel-heads by clamping the latter between bars D" D", attached to the frame V, said bars being each provided with a jaw or dog, *g'*.

At one side of the frame A there may be a circular saw, E', for sawing out the staves in proper form. The machine, however, will operate equally well on either sawed or rived staves. If the staves are winding, they may be readily adjusted on the bed H, so as to be properly dressed.

Having thus described my invention, what I claim as new, and desire to secure by Letters Patent, is—

1. The swinging segment-bed H, provided with the clamp-bar Q, and attached to a radius-bar, I, in combination with the rotary cutters D D', arranged to operate as and for the purpose herein set forth.

2. The particular manner of arranging the radius-bar I, so that its rack G may be connected with the driving-pinion *k* and be disengaged from it—to wit, by means of the frame J, catch M', and set-screw P, as described.

3. The yielding frame F', to which the gearing *j k* is fitted, when arranged with the spring *f*, set-screw *h*, and gearing E *i*, to operate as set forth.

4. The swinging supports and gage-bars U

U, when used in combination with the swing bed H and clamp-bar Q, as and for the purpose specified.

5. The sliding frame V, provided with the reversible bolster Y and clamp-bar Z, in combination with the rotary cutters C C and beveled rods C" C", as and for the purpose set forth.

6. The dog-bars D" D", when attached to the sliding frame V and used in connection with the cutters C C, as and for the purpose specified.

JACOB DOBBINS.
